E. ERICKSON

HEEL BEADING MACHINE

Original Filed Dec. 31, 1924

INVENTOR -
EDWARD ERICKSON, DEC'D.
MARY E. ERICKSON, EXECUTRIX,
BY HER ATTORNEY.

Nelson H. Howard

UNITED STATES PATENT OFFICE.

EDWARD ERICKSON, DECEASED, LATE OF BEVERLY, MASSACHUSETTS, BY MARY E. ERICKSON, EXECUTRIX, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-BEADING MACHINE.

Original application filed December 31, 1924, Serial No. 759,039. Divided and this application filed April 11, 1927. Serial No. 182,853.

This invention relates to beading machines and is illustrated as embodied in a machine especially adapted for use in beading the periphery of the top lift of a heel, this application being a division of the co-pending application of Edward Erickson, Serial No. 759,039, filed December 31, 1924, upon which Letters Patent of the United States No. 1,653,623 were granted Dec. 27, 1927.

10 Shoes having leather top lifts are commonly ornamented after they have been burnished by providing an indentation or beading around the peripheries of the top lifts. It is an object of the invention to provide a simple 15 and inexpensive beading machine which may be satisfactorily used to bead the peripheries of top lifts without the application of power, by movement of the work with respect to the tool.

20 The position of such beads or indentations with respect to the tread faces of the top lifts is varied in accordance with the style of the work and the taste of the manufacturer. With this in view, in accordance with features 25 of the invention, a novel construction and arrangement is provided for gaging the distance of the indentations from the tread face of the top lift, the arrangement being such that the operator may place the tool at 30 one heel breast corner and by a single continuous movement, readily cause the tool to bead the top lift around its whole outer periphery.

As illustrated, the beading machine comprises a beading tool in the form of a freely rotatable disk and combined with the tool is a disk-shaped gage member also freely rotatable and adjustable axially to vary its separation from the indenting disk. The illustrated gage has rounded peripheral edges to avoid damage to the work. These and other features of the invention are more fully disclosed in the following description taken in connection with the accompanying drawings, in which

45 Fig. 1 is a perspective view of the novel beading tool mounted upon a suitable support; and

50 Fig. 2 is a section taken through the tool along its axis.

A top lift beading tool 10 is mounted upon

a tool supporting head 12 held upon a standard 14 by means of set screw 16. The tool supporting head 12 has a lateral boss 18 for the support of a stud 20 upon which the tool may be mounted. It will be understood that the standard 14 will be provided with a suitable base (not shown) by means of which it may be mounted upon a bench in convenient position for the presentation of a heel 15 to the tool by an operator to make a bead 17 around the periphery of the top lift.

From an inspection of Fig. 2, it will be seen that there is provided a headed supporting stud 20 adjustably held in position in the boss by means of a set screw 22. The top lift beading tool 10, which preferably is mounted for free rotation upon the stud 20, comprises a disk portion 24, the edge of which is used to indent the work by rolling contact therewith, and a sleeve portion 26 surrounding the stud 20 and this top lift tool is positioned upon the stud by engagement with the head of the stud and the end of the boss 18, thereby preventing axial movement of the tool while allowing free rotation thereof. The outside of the sleeve portion 26 is threaded and a gage member 28 having the form of a disk is adjustably positioned upon said sleeve by threaded engagement therewith and is held in adjusted position by means of a lock nut 30. It will be noted that the outer periphery of the disk-shaped gage member 28 is smooth and rounded so that there is no danger of marking the work in case the operator allows the shoe to slip and come into contact with the edge of the gage. As will be seen from Fig. 1, the end of the stud 20 and the end of the top lift beading tool 10 are provided with a screw driver slot 32 to allow the user to hold the tool from rotation when it is desired to adjust the gage member on the sleeve portion 26.

Inasmuch as the machine is used in the manner illustrated in Fig. 1 by resting the tread face of the top lift against the flat face of the gage disk 28, the position of the beading line upon the heel or its distance from the tread face of the heel is determined by proper adjustment of the gage member 28 upon the sleeve of the beading tool to vary the distance between said flat face of the

disk 28 and the edge of the disk portion 24 of the beading tool.

With this arrangement both the beading tool 10 and the gage disk 28 are freely rotatable upon the stud 20 and the operator will present the top lift of the heel 15 to the disk portion 24 of the top lift tool 10 so that it engages the top lift at one corner of the heel with the tread face of the heel rested against the flat face 34 of the disk-shaped gage member 28. The operator then passes the work downwardly and across and upwardly with a single continuous movement in such manner that the tool is brought into engagement with the whole of the outer periphery of the top lift. The indentation of the work will be effected by the pressure of the work against the beading tool as the operator moves it around the tool in contact therewith. The position illustrated in Fig. 1 is intermediate between the extreme positions of the work during the whole cycle of movement.

The invention having been described, what is claimed as new and desired to be secured by Letters Patent is:

1. A heel-beading machine including a standard having a plane surface, a headed supporting stud projecting from said plane surface, a beading tool member comprising a disk-shaped indenting tool and a disk-shaped gage member for said tool mounted concentrically on said supporting stud and arranged to coact respectively with adjacent intersecting surfaces of a heel, one of said members being freely rotatable on said stud, the distance of the beading line from the adjacent edge of work operatively presented to the tool being determined by the distance between the beading tool and the flat face of the disk, and means for adjustably holding said stud in said standard to allow free rotation of the member rotatably mounted thereon while restricting axial movement of said rotatable member by the cooperation of the head of the stud and the plane surface of the standard with opposite ends of said member.

2. A heel-beading machine comprising a support, a beading tool comprising a disk-shaped indenting tool, a disk-shaped gage member for said tool mounted concentrically on said support and arranged to coact respec-

tively with adjacent intersecting surfaces, one of said disks being freely rotatable, the distance of the beading line from the adjacent edge of work operatively presented to the tool being determined by the distance between the beading tool and the flat face of the disk, and means for relatively adjusting said tools to vary this distance.

3. A heel-beading machine, comprising a support, a freely rotatable disk-shaped beading tool, and a gage member for said tool comprising a flat disk larger than the beading tool and having its peripheral edges rounded to avoid damage from accidental contact of the work therewith, said tool and said gage being mounted on said support, the distance of the beading line from the adjacent edge of work operatively presented to the tool being determined by the distance between the beading tool and the flat face of the disk.

4. A heel-beading machine comprising a support, a beading tool comprising an indenting member having a disk-shaped portion and a sleeve portion mounted for free rotation on said support, a gage member threaded on said sleeve for adjustment of its position with respect to the disk-shaped portion of the indenting member, thereby adjustably to gage the distance of the beading indentation from the tread face of a top lift rested against said gage member, means for holding said tool against rotation as the gage member is turned thereon for adjustment, and means to lock said gage in adjusted position.

5. A beading machine comprising a standard, a headed supporting stud mounted therein, an indenting tool having a sleeve portion surrounding and freely rotatable upon the stud between said standard and the head of the stud, said tool having a work-engaging indenting portion adjacent to the headed end of the stud, a disk-shaped gage member adjustably mounted upon said sleeve, and means for locking the gage member in adjusted position.

In testimony whereof I have signed my name to this specification.

MARY E. ERICKSON,
*Executrix of the Will of Edward Erickson,
Deceased.*
